SPRING SUPPORT ATTACHMENT

Alfred H. Bennett, Hyde Park, Pa.

Application February 15, 1952, Serial No. 271,816

7 Claims. (Cl. 5—244)

1

This invention relates to an attachment for bed springs or other spring frames for furniture used for supporting mattresses and cushions, and has for its primary object to provide a support capable of being adjustably connected to a spring frame and located adjacent a portion of the frame where the springs have become weakened to correct sagging of a mattress or cushion in certain areas thereof normally required to support a preponderance of the weight to which the mattress and springs are subjected to eliminate a sagging condition of the mattress or cushion in the area thereof located over weakened springs of the spring frame.

More particularly, it is an aim of the present invention to provide an attachment of extremely simple construction a group of which may be detachably clamped to a spring frame over the weakened springs thereof to eliminate sagging of a cushion or mattress supported on the frame in the area thereof which is subjected to the greatest weight.

A further object of the invention is to provide an attachment which may be applied to a spring frame beneath the area of a mattress or cushion normally subjected to the greatest weight to reinforce and strengthen the spring frame portion or portions disposed therebeneath and to more equally distribute the weight normally borne by certain overloaded springs of the frame to prevent weakening of said springs.

A further object of the invention is to provide a spring frame attachment of extremely simple construction which may be very economically manufactured and sold and which is capable of being quickly and easily applied to or removed from a spring frame and adjustably positioned in any desired location thereon to more equally distribute the load borne by the frame.

Various other objects and advantages of the invention will hereinafter become more fully apparent from the following description of the drawing, illustrating a presently preferred embodiment thereof, and wherein:

Figure 1 is a top plan view showing the invention applied to the upper frame section of a box-type bed spring;

Figure 2 is a cross sectional view of the bed spring shown mounted in the frame of a bed with a mattress shown in end elevation supported thereon;

Figure 3 is a fragmentary side elevational view partly in section and on an enlarged scale of the attachment as it will appear in an applied position;

2

Figure 4 is a cross sectional view of the attachment taken substantially along a plane as indicated by the line 4—4 of Figure 3;

Figure 5 is a fragmentary side elevational view of one part of the attachment, and

Figure 6 is a vertical sectional view, partly in side elevation of another part of the attachment.

Referring more specifically to the drawing, the spring attachment, designated generally 7 and comprising the invention, comprises a substantially rigid elongated member 8 which as illustrated is of hollow or tubular form, but which could obviously be a solid rod, if desired. The rigid elongated member or tube 8 is provided with externally threaded ends 9 and 10. Each end of the tube 8 is provided with aligned slots 11 which open outwardly thereof and extend inwardly to beyond the inner end of the threaded portion 9 or 10. An internally threaded cap 12 is detachably mounted on each end of the tube 8 by engagement with the threaded portion 9 or 10 thereof. A spreading element 13 is mounted in each cap 12 and centrally thereof to fit into the end of the tube 8 on which the cap 12 is mounted. Said spreading element 13 is of a diameter to snugly engage in the tube end and is preferably provided with a rounded outer end 14 to assist in guiding the spreader 13 into the tube end. A stem 15 extends from the opposite, inner end 20 of the spreader 13 through a central opening 16 in the end wall 17 of the cap 12, said opening 16 having a flared outer end 18 to receive the flared outer portion of the stem 15, as indicated at 19. The stem 15 nondetachably connects the spreader 30 13 to the cap 12 and if desired may turnably fit the opening 16 to swivelly mount the spreader 13 in the cap.

Referring to Figures 1 and 2, to illustrate a preferred application and use of the spring attachment 7, a bed spring of the box-type is illustrated in Figures 1 and 2 and is designated generally 20. A base portion 21 of the bed spring 20 is shown supported on portions 22 of a bed frame. The base 21 supports a plurality of coiled springs 23 which are suitably tied together in a conventional manner and which includes a plurality of transverse rows of the coil springs 23, as illustrated in Figure 1. The bed spring 20 also includes a rectangular top frame 24 formed of 40 heavy gauge wire or rod stock, which is disposed around the springs 23. Any number of the spring attachments 7 may be utilized with the bed spring 20. Ordinarily, three or four of the attachments are employed over the area of the bed spring 50 which normally bears the most weight i. e., the

portion thereof from adjacent the head of the bed to midway of or somewhat beyond a midpoint of the ends of the bed spring. As seen in Figure 1, four of the attachments 7 are shown detachably clamped to longitudinal side portions 25 of the top frame 24. Two of the attachments 7 are shown disposed approximately intermediate of the ends of the bed spring 20 and the other two attachments 7 are shown disposed near one end of the bed spring, which may be assumed to be located near the head of the bed. Each attachment 7 is applied by first removing the two caps 12 and then positioning the elongated member or tube 8 transversely of the top frame 24 and at a slight angle to the transverse position of the tube as illustrated in Figure 1, so that the side portions 25 of the spring frame 24 can be engaged in the notches 11. The caps 12 are then applied to the threaded ends 9 and 10 and tightened so that the rounded ends 14 of the spreaders 13 will engage the frame sides 25 to clamp them between portions of the tube located at the inner ends of the slots 11 and the rounded ends 14 of the spreaders 13. The spreaders 13 also function to prevent collapsing of the slotted ends 9 and 10 so that the threaded portions of the caps will correctly fit the threads of the tube portions 9 and 10. It will thus be seen that each attachment 7 may be effectively clamped in any desired position to the bed spring 20 and transversely thereof. Each tube 8 is preferably located directly over a transverse row of coil springs 23. A mattress 26 supported on the bed spring 20 has portions thereof supported by the attachments 7. It will be readily apparent that the weight borne by the portion of the mattress disposed over the supports 7 will be distributed equally from side-to-side of the bed spring so that each of the coil springs disposed beneath each tube or elongated member 8 will support substantially an equal portion of the weight on the tube 8. Accordingly, the bed springs will be prevented from sagging at the portion thereof which normally supports the most weight and the mattress 26 will likewise be prevented from sagging over the weakened portions of the bed spring and will be supported more firmly in the area resting on the supports 7 which normally bears the most weight. The support 7 may obviously be utilized for strengthening and reinforcing a weakened bed spring by being positioned over the coil springs thereof which have partially lost their resiliency and become weakened to eliminate a sagging of the bed spring and a mattress supported thereby. Likewise, the supports 7 may be used with new bed springs or with bed springs which have not commenced to sag to reinforce the portion thereof subjected to the most weight to prevent weakening of the coil springs and sagging of the bed spring and to provide a firmer support for the area of a mattress normally subjected to the most weight. The attachment may also be utilized to strengthen a bed spring which has become weakened, which is too soft or which possesses too much resiliency.

It will be understood that the attachment 7 may be used in the same manner with other types of furniture springs providing spring supports for cushions or the like. Various other modifica-

tions and changes are likewise contemplated and may obviously be resorted to, without departing from the spirit or scope of the invention as hereinafter defined by the appended claims.

5 I claim as my invention:

1. An attachment for a box-type bed spring comprising an elongated rigid member having longitudinally extending slots opening outwardly of the ends thereof adapted to engage portions 10 of the parallel longitudinal sides of the top frame of a supporting spring structure, and cap members detachably connected to the ends of the elongated member for retaining the parallel frame portions in said slots and for clamping 15 the elongated member thereto to position the attachment above and in engagement with the upper end of a transverse row of coil springs of the spring structure.

2. An attachment as in claim 1, said slotted 20 ends of the elongated member being threaded externally, and said caps being internally threaded and threadedly engaging said threaded ends for detachably mounting the caps thereon.

3. An attachment as in claim 1, said elongated 25 member being tubular.

4. An attachment as in claim 3, a spreading member connected to and supported in each of the caps and sized to fit into an end of the tubular member when the cap is threaded thereon 30 and bearing against the parallel side portion of the spring frame which extend through the tubular member for clamping the tubular member thereto.

5. An attachment as in claim 4, said spreader 35 being sized to snugly fit the tubular member to prevent collapsing of the slotted externally threaded end thereof engaged by said cap.

6. An attachment as in claim 5, said spreader being swivelly mounted in the cap.

7. The combination with a box-type bed spring 40 including a top frame surrounding the upper portion of the coil springs of the bed spring and which top frame includes substantially parallel side portions, of an elongated rigid member having aligned longitudinally extending slots opening outwardly of the ends thereof and detachably engaging portions of the parallel side portions of said top frame and resting on the upper convolutions of a transverse row of coil springs, and cap members detachably connected to the ends of said elongated member for clamping the parallel frame portions in the inner ends of said slots to anchor the elongated member to said top frame.

55 ALFRED H. BENNETT.
